CLAIM

The ornamental design for a display screen or portion thereof with a graphical user interface, as shown and described.

DESCRIPTION

FIG. 1 is a front view of a display screen or portion thereof with a graphical user interface showing one embodiment of our new design; and,

FIG. 2 is a front view of a display screen or portion thereof with a graphical user interface showing another embodiment of our new design.

The dot dashed broken line showing the display screen or portion thereof forms no part of the claimed design. The dashed broken line showing portions of the graphical user interface forms no part of the claimed design.
